UNITED STATES PATENT OFFICE

NATHAN FEIN, OF READING, PENNSYLVANIA

DESIGN FOR A SANDAL OR SIMILAR ARTICLE

Application filed January 25, 1932. Serial No. 42,807. Term of patent 14 years.

To all whom it may concern:

Be it known that I, NATHAN FEIN, a citizen of the United States, residing at Reading, county of Berks, and State of Pennsylvania, have invented a new, original, and ornamental Design for a Sandal or Similar Article, of which the following is a specification, reference being had to the accompanying drawing, forming a part thereof.

The figure is a perspective view of a sandal or similar article, showing my new design.

I claim:

The ornamental design for a sandal or similar article as shown.

NATHAN FEIN.
